DESIGN FOR AN OUTBOARD MOTOR

Finn T. Irgens, Wauwatosa, Wis., assignor to Outboard Motors Corporation, Milwaukee, Wis., a corporation of Michigan

Application June 14, 1934, Serial No. 52,179

Term of patent 7 years

To whom it may concern:

Be it known that I, Finn T. Irgens, a citizen of the United States, residing at Wauwatosa, in the county of Milwaukee and State of Wisconsin, have invented a new, original, and ornamental Design for an Outboard Motor, of which the following is a specification, reference being had to the accompanying drawing, forming part thereof.

In the drawing:

Figure 1 illustrates a perspective view of an outboard motor embodying the invention.

Figure 2 is a top plan view of the outboard motor shown in Figure 1.

The lower unit, being of conventional design, is shown in broken lines. The power head which is the dominant feature of the present design, is shown in heavy lines.

I claim:

The ornamental design for an outboard motor as shown and described.

FINN T. IRGENS.
